CLAIM

The ornamental design for a portable radio battery eliminator, as shown and described.

DESCRIPTION

FIG. 1 is a top, front, and left side perspective view of a portable radio battery eliminator showing our new design; FIG. 2 is a bottom side plan view thereof; FIG. 3 is a rear side elevational view thereof; FIG. 4 is a right side elevational view thereof; and, FIG. 5 is a top, rear, left side perspective view thereof. The dotted lines as shown in the drawings are for illustrative purposes only and form no part of disclosed invention.
